UNITED STATES PATENT OFFICE.

NELLIE L. HARMON, OF BOWERSTON, OHIO.

COMBINED BUMPER AND FEEDER.

Application filed March 5, 1926. Serial No. 92,522.

This invention relates to means for handling cars in mining and other operations where the travel of cars upon tracks is controlled, and more particularly to what I term a combined bumper and feeder.

One of the main objects of the invention is to provide an apparatus of the character stated of comparatively simple construction and operation which will prevent the cars from being subjected to excessive jars and strains. A further object is to provide an apparatus including shock absorbing means associated with bumper members for contact with the bumpers of the cars so as to relieve the car axles of strains which would tend to break the same.

Another object is to provide an apparatus of this character which can be operated at high speed so as to feed cars onto dumps, cages, and other structures very rapidly effecting a material saving of time, as compared to feeders now commonly used, which is an important consideration in mining operations. Other objects will appear from the detailed description.

In the drawings:

Fig. 1 is a plan view of a combined bumper and feeder constructed in accordance with my invention.

Fig. 2 is a side view of the same.

Fig. 3 is a side view of the bumper block and members carried thereby and associated parts.

Fig. 4 is a section taken substantially on line 4—4 of Fig. 1.

Fig. 5 is a plan view of a modified form of the combined bumper and feeder.

Fig. 6 is a side view of the combined bumper and feeder illustrated in Fig. 5.

Fig. 7 is a detail of the spring and associated parts for completing the throw of the rock shaft in either direction.

Fig. 8 is a detail of the hinged trip arm.

Fig. 9 is a plan view of another modified form of the combined bumper and feeder.

Fig. 10 is a side view of the form illustrated in Fig. 9.

For the purposes of description I have illustrated my combined bumper and feeder as used in connection with a cage, though it is equally well adapted for use in connection with various types of dumps and other structures used in mining operations. Also,

this combined bumper and feeder can be used for controlling the travel of cars on tracks in other positions, such as controlling the feeding of cars over a knuckle, down an incline, onto scales, etc.

My invention is used in connection with a track A including rails a upon which cars travel. Preferably, the portion of the track upon which the bumper and feeder is mounted is inclined at a sharper grade than the remainder of the track so as to provide a bend or knuckle B' over which the cars are fed. When the cars are held on track A the second car is so positioned that the front wheels thereof are a short distance beyond the stops 6 so that this car will readily start down the more steeply inclined portion of the track when desired. This construction is known and need not be further described in detail.

A rock shaft 1 is rockably mounted between rails a in bearings 2 secured to cross ties or other suitable supports. The cross head 3 is secured to shaft 1 and the arms of this cross head are connected by links 4 to arms 5 of stops 6 which are slidably and rockably mounted on pintle rods 7 secured in bearing members 8 which are secured to the rails a. Cushion springs 9 are mounted about rods 7 and confined between stops 6 and the inner bearing members 8 to cushion movement of the stops. The connection between the stops and the shaft, as well as the method of mounting and cushioning the stops, is known and need not be described in detail. The stops are thus mounted adjacent the rails a for movement into open and closed positions relative thereto. Shaft 1 is turned in stop opening direction by a tension spring 10 the inner end of which is secured to a finger 11 of a collar 12 secured on shaft 1. The outer end of this spring is secured to a plate 13 which is secured to and depends from one of the rails a, or may be anchored in any other suitable or preferred manner.

A plate 14 is secured between rails a in advance of stops 6. A block 15 is slidably mounted on the rods 16 which are mounted in supporting members 17 and 18 secured to plate 14. These rods 16 are disposed in parallelism with the rails a and support the block 15 for movement longitudinally of

the track. Movement of the block in a direction away from stops 6 is cushioned by springs 19 and 20 mounted about the rods and confined between the block and supporting member 18. The spring 20 is appreciably stronger than the springs 19 and acts to cushion the block 15 after the springs 19 have been placed under compression, all of the springs coacting to absorb any shocks 10 or jars incident to the stopping of a car by the bumper members 21 carried by the block. Members 21 are mounted for vertical sliding movement through block 15 and are connected at their lower ends by a bar 22. The 15 ends of this bar are connected by springs 23 to lugs 24 extending from the end of block 15, these springs acting to hold bumper members 21 in raised position. An arm 25 is secured on shaft 1 and is provided with a 20 finger 26 which extends above bar 22. When the shaft is rocked or turned in stop closing direction, bar 22 is depressed by finger 26 so as to lower the bumper members 21 out of contact with the bumper C' of a car C 25 supported upon the track above members 21. At the same time that the bumper members 21 are depressed, the stops 6 are closed so as to be positioned in advance of the front wheels of the succeeding car. This permits 30 the first car to travel along the track past the members 21 and the second car moves along the track a short distance until its front wheels contact with the stops 6. As the travel of this second car is but very slight, 35 the springs 9 act to effectively cushion this car and the axle of the front car of the trip which is held back on the track is not subjected to severe strains or jars such as would tend to break the axle. This is a very im- 40 portant consideration in connection with cars having light axles, or cars which are heavily loaded. The first car which has been released from the bumper members 21 can travel past these bumper members onto a 45 dump, cage, or other suitable structure, or can be directed from the track A onto some other track. For convenience in description I have illustrated this apparatus as used in conjunction with a cage B, which is pro- 50 vided with a trip member 27 disposed to contact with finger 28^a of a trip crank 28 secured on the end of shaft 1 adjacent the shaft or pit in which the cage operates. As the cage is lowered into loading position member 55 27 contacts with finger 28^a and turns the shaft 1 in stop closing direction, moving the bumper members 21 downwardly out of contact with bumper C' of the first car C, the members 21 being depressed sufficiently to 60 insure that they will clear the axles of the car. This permits the first car C to travel downwardly onto the cage, the second car being held back by the stops 6. The cage B is provided with any known or suitable

means for receiving the car and retaining it 65 in position upon the cage. As the cage is raised trip crank 28 is released and spring 10 acts to turn the shaft 1 in stop opening direction. This opens the stops 6 and raises the bumper members 21 permitting the trip 70 to move downwardly or forwardly on track A until the first car contacts with the bumper members. The springs 19 and 20 act to absorb any jars or shocks due to contact of the bumper C' of the car with the members 75 21. As the members 21 and block 15 and associated parts possess great strength all danger of injury to the feeder when the cars move forwardly is eliminated. It is also to be noted that the bumper C' of the 80 car contacts with the members 21 so that the axles of the car are not subjected to any jars or strains. This effectually eliminates all danger of breakage of the car axles such as is apt to occur where cars are used with 85 comparatively light or thin axles, or the cars are very heavily loaded. This is an important consideration in that movement of the cars is effectually cushioned and all danger 90 of injury to the cars or to the feeder is effectually eliminated. When the cage is returned to loading position the shaft 1 is again rocked in stop opening direction and the operation above described is repeated. Where the apparatus is used on a track for 95 feeding cars to a cage dump, scale or other structure and it is not practical to operate the apparatus by the cage or dump, the shaft 1 may be turned in stop opening direction by a pedal or lever connected thereto in a known manner. The means for turning the shaft 1 will vary to a certain extent in accordance with the use to which the feeder is put but the operation of the feeder itself 100 will be the same in all instances. 105

In Figures 5 and 6 I have illustrated a modified form of feeder in which an arm 29 is secured on shaft 1 in advance of the bumper construction. This arm is positioned to be engaged by an arm 30 secured on a stub shaft 31 rockably mounted on one of the rails a. A second arm 32 is secured on the outer end of the stub shaft and is provided with a treadle plate 33 which is adapted, when depressed, to fit into a cut out 34 in the ball of the rail, the plate 33 being flush with the tread of the rail so as to form a continuation thereof. The trip crank 28 illustrated in Figures 1 and 2 is replaced by a trip arm 35 which has a nose portion 36 hinged at 37 to the body portion 35^a of the arm in such manner as to permit relative upward movement of nose portion 36 while preventing downward movement of this member. A trip member 38 is secured on cage B and disposed to contact with the nose 36 of arm 35 when the cage is lowered into loading position. In this form a crank arm 110 115 120 125

39 is secured on the outer end of shaft 1 and is connected by a tension spring 40 to a plate 41 secured to one of the rails *a*. This spring is so disposed as to complete the throw of the shaft in either direction after the shaft has been turned a predetermined distance in such direction, the spring also acting to normally hold the shaft against turning movement. An arm 42 is secured on shaft 1 and is provided with a finger 43 which extends above bar 22, this arm being so disposed that it is in substantially vertical position when the bumper members 21 are lowered. As the cage B moves into loading position member 38 contacts with nose 36 of arm 35 and turns shaft 1 in stop closing direction, the throw of the shaft in such direction being completed by spring 40 which then acts to hold the shaft in such position with arm 42 disposed substantially vertical so as to hold the bumper members 21 depressed. When the car C has travelled a short distance beyond the bumper construction the front wheel of this car contacts with treadle plate 33 depressing the same and, by means of arms 29 and 30, turning the shaft 1 in stop opening direction. The throw of the shaft in stop opening direction is completed by spring 40 which acts to hold the shaft in this position. This movement of the shaft turns arm 42 in such position as to permit the bumper members 21 to be raised by springs 23 into position to contact with bumper C' of the first or entering car of the trip. Upon return of the cage to loading position the shaft is again turned in stop opening direction and the operation above described is repeated. In this form of feeder and bumper, the front car of the trip is permitted to travel as far as the bumper members 21 while the cage is being raised, the car being released from the stops 6 prior to entry of the first car onto the cage. This renders it possible to cut out the cars from the trip and feed them onto the cages, dump, scales or other structure, very rapidly, which is frequently a very important consideration in mining and other operations where the travel of cars on tracks is to be controlled.

In the modified form illustrated in Figures 9 and 10, arms 43, constructed similarly to arm 35, are secured on shaft 1 adjacent the ends of the bumper construction. These arms are disposed to engage beneath foot elements 44^a of angle members 44 extending downwardly from bars 45 connected at one end by a retaining rail 46 rigidly secured to bars 45 and disposed adjacent and parallel to one of the track rails *a*. When cage B approaches loading position trip member 38 contacts with arm 37 turning shaft 1 in stop closing direction and lowering members 21. The wheels of the entering car bear upon retaining rail 45 until after the turning

movement of the shaft in stop closing direction is completed, during which the movable or nose members of levers 45 are caused to pass beneath elements 44^a of members 44. As soon as trip member 38 passes out of contact with lever 35 the shaft is released but is held against turning movement under the influence of spring 10 by arms 43 and members 44, rail 46 being held depressed by the wheels of the released car. Rail 46 is released when the car passes beyond the rail, and this permits raising of the rail, spring 10 acting to turn the shaft 1 in stop opening direction, this movement of the shaft raising members 21 into operative position for contact with the bumper of the second car. Turning of the shaft into stop opening position also raises arms 43 into normal position above elements 44^a of members 44. Upon return of the dump to loading position the operation described is repeated. The provision of the retaining rail 46 and associated parts ensures that the members 21 will not be raised and the stops 6 will not be opened until the released car has passed well beyond the bumper construction. This imparts an additional factor of safety and accuracy to the apparatus as a whole.

As above indicated, and as will be understood, changes in construction and arrangement of parts of the invention may be resorted to without departing from the field and scope of the same, and I intend to include all such variations, as fall within the scope of the appended claims, in this application in which the preferred forms only of my invention are disclosed.

What I claim is:

1. In a combined feeder and bumper, a track, stops movable into and out of car holding position relative to the track, members mounted on the track beyond the stops and movable into and out of position to contact with the bumper of a car travelling on the track, and car controlled means for moving the stops into car holding position and said members into inoperative position, and vice versa.

2. In a combined feeder and bumper, a track, stops movable into and out of car holding position relative to the track, members mounted on the track beyond the stops and movable into and out of position to contact with the bumper of a car travelling on the track, a rockably mounted shaft, means for moving the stops into inoperative position and said members into operative position and vice versa, in accordance with rocking of the shaft, car controlled means for rocking the shaft.

3. In a combined feeder and bumper, a track, stops movable into and out of car holding position relative to the track, a bumper structure including members mounted to be raised and lowered into and out of

position to contact with the bumper of a car travelling on said track, and car controlled means for moving the stops out of car holding position and raising said members, and vice versa.

4. In a combined feeder and bumper, a track, stops movable into and out of car holding position relative to the track, a bumper structure including members mounted to be raised and lowered into and out of position to contact with the bumper of a car travelling on said track, means for moving the stops into car holding position and lowering said members, and vice versa, and car actuated means for raising said members and moving the stops out of car holding position when the car has passed beyond the bumper members.

5. In a combined feeder and bumper, a track, stops mounted adjacent the rails of the track and movable into and out of closed position relative thereto, a bumper structure beyond the stops including members mounted to be raised and lowered into and out of position to contact with the bumper of a car travelling on the track, a rockably mounted shaft, connections between the shaft and the stops for opening and closing the stops in accordance with rocking of the shaft, means for raising said bumper members when the shaft is turned in stop opening direction, and vice versa, and car controlled means for rocking the shaft.

6. In a combined feeder and bumper, a track, stops mounted adjacent the rails of the track and movable into and out of closed position relative thereto, a bumper structure beyond the stops including members mounted to be raised and lowered into and out of position to contact with the bumper of a car travelling on the track, means for lowering the bumper members and closing the stops and vice versa, means for holding said members lowered and the stops closed, and car actuated means for releasing the bumper members and the stops and for raising said members and opening the stops when the car has passed beyond the bumper members.

50 7. In a combined feeder and bumper, a track, stops mounted adjacent the rails of the track and movable into and out of closed position relative thereto, a block slidably mounted on the track beyond the stops, means cushioning movement of the block in a direction away from the stops, bumper members carried by the block and mounted to be moved into and out of position to contact with the bumper of a car travelling on the track, and car controlled means for opening said stops and for moving said members into position to contact with the bumper of the car, and vice versa.

65 8. In a combined feeder and bumper, a track, supporting members on the track, rods

carried by said members, a block slidably mounted on the rods for movement longitudinally of the track, means cushioning movement of the block, bumper members slidably mounted on the block for vertical movement, and means for raising and lowering said bumper members.

9. In a combined feeder and bumper, a track, supporting members on the track, rods carried by said members, a block slidably mounted on the rods for movement longitudinally of the track bumper members mounted in said block, means cushioning movement of the block, means urging the bumper members into raised position, and means for moving said bumper members into lowered position.

10. In a combined feeder and bumper, a track, supporting members on the track, rods carried by said members, a block slidably mounted on the rods for movement longitudinally of the track bumper members mounted in said block, means cushioning movement of the block, means urging the bumper members into raised position, a rockably mounted shaft, and means for lowering the bumper members when the shaft is rocked in one direction.

11. In a combined feeder and bumper, a track, supporting members on the track, rods carried by said members, a block slidably mounted on the rods for movement longitudinally of the track bumper members mounted in said block, means cushioning movement of the block, a bar connecting the bumper members, means acting to raise the bar while permitting it to be depressed, a rockably mounted shaft, and an arm secured on the shaft and having a member extending over the bar for depressing the same when the shaft is rocked in one direction.

12. In a combined feeder and bumper, a track, supporting members on the track, rods carried by said members, a block slidably mounted on the rods for movement longitudinally of the track, bumper members mounted on the block and movable into and out of position to contact with the bumper of a car travelling on the track, means for moving said bumper members into inoperative position, and means for moving the bumper members into operative position after the car has passed beyond the same.

13. In a combined feeder and bumper, a track, supporting members on the track, rods carried by said members, a block slidably mounted on the rods for movement longitudinally of the track, bumper members mounted on the block and movable into and out of position to contact with the bumper of a car travelling on the track, means for moving said bumper members into inoperative position and for holding them in such position, means urging the bumper members into operative position, and means for re-

leasing the bumper members after the car has passed beyond the same.

14. In a combined feeder and bumper, a track, supporting members on the track, 5 rods carried by said members, a block slidably mounted on the rods for movement longitudinally of the track, bumper members mounted on the block and movable into and out of position to contact with the bumper of a car travelling on the track, means for moving said bumper members into inoperative position and for holding them in such position, means urging the bumper members into operative position, and car actuated means for releasing the bumper members after the car has passed beyond the same.

15. In a combined feeder and bumper, a track, stops mounted adjacent the rails of the track and movable into open and closed position relative thereto, bumper members on the track spaced from the stops and movable into and out of position to contact with the bumper of a car on the track, a rockably 20 mounted shaft, connections between the shaft for closing and opening the stops in accordance with rocking of the shaft, means urging the shaft in stop closing direction, means urging the bumper members into operative position, the shaft and the bumper members being provided with cooperating means for moving the bumper members into inoperative position when the shaft is turned in stop closing direction and for releasing said members when said shaft is turned in stop opening direction, and car actuated means for turning the shaft in stop opening direction.

16. In a combined feeder and bumper, a track, stops mounted adjacent the rails of the track and movable into open and closed position relative thereto, bumper members on the track spaced from the stops and movable into and out of position to contact with the bumper of a car on the track, a rockably 45 mounted shaft, connections between the shaft for closing and opening the stops in accordance with rocking of the shaft, means urging the shaft in stop closing direction, means urging the bumper members into operative position, means for moving the bumper members into inoperative position and holding them in such position when the shaft is turned in stop closing direction, and car actuated means for turning the shaft in stop opening direction and releasing the bumper members when a car has passed beyond the same.

17. In a combined feeder and bumper, a track, stops mounted adjacent the rails of the track and movable into open and closed position relative thereto, bumper members on the track spaced from the stops and movable into and out of position to contact with the bumper of a car on the track, a rockably 60

mounted shaft, connections between the shaft and the stop for closing and opening the stops in accordance with rocking of the shaft, means urging the shaft in stop closing direction, means urging the bumper members into operative position, means for moving the bumper members into inoperative position and holding them in such position when the shaft is turned in stop closing direction, and means actuated by a car 70 travelling on the track beyond the bumper members for turning the shaft in stop opening direction and releasing said members.

18. In a combined feeder and bumper, a track, stops mounted adjacent the rails of the track and movable into open and closed position relative thereto, bumper members on the track spaced from the stops and movable into and out of position to contact with the bumper of a car on the track, a rockably 80 mounted shaft, connections between the shaft for closing and opening the stops in accordance with rocking of the shaft, means for completing turning of the shaft in either direction and for holding it in position, 85 means urging the bumper members into operative position, an arm secured on the shaft, a member mounted on the track and disposed to be depressed by a car travelling on the track beyond the bumper members, and an 90 arm connected to the track member for turning movement therewith and positioned to contact with the shaft arms, said arms being disposed to turn the shaft in stop opening direction when the track member is depressed.

19. In a combined feeder and bumper, a track, stops movable into open and closed positions relative to the track rails, a bumper structure including members movable into 105 and out of position to contact with the bumper of a car traveling on the track, means for opening the stops and moving the bumper members into operative position and vice versa and for urging the stops in closing direction, and car controlled means for holding the stops open and then releasing them after a released car has passed beyond the bumper structure.

20. In a combined feeder and bumper, a track, stops movable into open and closed positions relative to the track rails, a rockably 110 mounted shaft, connections between the stops and the shaft for opening and closing said stops in accordance with turning 120 of the shaft, a bumper structure beyond the stops and including members movable into and out of position to contact with the bumper of a car traveling on the track, yielding means urging the bumper members into operative position, yielding means urging the shaft in stop opening direction, the bumper structure and the shaft having cooperating means for moving the bumper members into inoperative position when the shaft is turned 125 130

in stop closing direction, a retaining rail adjacent the bumper structure and disposed closely adjacent and parallel to one of the track rails to be held in lowered position by the wheels of the car, said retaining rail having free upward movement when released, and cooperating means associated

with said retaining rail and with the shaft for holding the shaft in stop closing position when the retaining rail is held in lowered position and for releasing the shaft when the retaining rail is released.

In testimony whereof I affix my signature.
NELLIE L. HARMON.
